DIAL SWITCHING TELEPHONE SYSTEM

William Hatton, Leslie Baines Haigh, and
Ladislas Kozma, Antwerp, Belgium, assignors
to Western Electric Company, Incorporated,
New York, N. Y., a corporation of New York

Application April 7, 1938, Serial No. 200,656
In Great Britain October 31, 1936

9 Claims. (Cl. 179—18)

This invention relates to electrical communication systems and more particularly, though not exclusively, to automatic ticketing equipment for use in such systems.

5 One object of the invention is to provide improved substation identifying equipment which allows identification of any substation of an exchange in an economical and expeditious manner.

10 With this object in view one feature of the invention comprises a telecommunication exchange system comprising subscriber identifying equipment, characterized in this, that two stages of subscriber identifying switches or the like look for marking conditions applied to a circuit connection terminating at one end in a subscriber's line to be identified.

15 Another object of the invention is to provide improved means for ensuring that operating procedure in interstation connections is not prejudiced by the use of faulty equipment.

20 With this object in view a second feature of the invention comprises an electrical communication system comprising a number of similar equipments, any idle one of which can be used in a connection, characterized by automatic test circuits in said equipments which test certain devices therein for faults immediately the equipments are taken into use, and by circuits closed 25 if a fault exists in an equipment to disconnect and busy the equipment, to cause another equipment to be connected up in its place, and to give an alarm.

25 According to another feature of the invention, the same calling line identification equipment can be used for identifying calling subscribers of a plurality of different hundred-line groups. The identification may be made in a plurality of stages.

30 According to a further feature, the calling party's number and the record of the duration of the connection can both be made without delaying the normal release of a connection.

35 According to a further feature of the invention, a minimum holding time for a completed connection is enforced unless before that time expires certain records incidental to charging for the connections have been made.

40 According to a further feature of the invention, common equipment used temporarily (e. g., for automatic ticketing purposes) is tested when seized, and, if defective, is dropped and replaced by a similar equipment which is also tested before use. For instance, a common voice-frequency 45 signal-receiving valve circuit may be so tested.

This test takes place without prejudice to the correct progress of the call or the completion of a full automatic ticketing record for the call.

45 The invention will be more clearly understood from the following description of two embodiments of the invention shown in the accompanying drawings in which:

50 Fig. 1 shows part of a subscriber's line circuit, a first line finder, a second line finder, and a first group selector together with a complete identification line finder. The latter is one of a group of identical circuits and is adapted to have access to the subscriber's lines served by a plurality of groups of first line finders;

55 Fig. 2 shows an identification control circuit which is one of a group of identical circuits and is adapted to have access through its finder CF to a plurality of identification finders belonging to one or more groups of such finders and through its finder IF to a plurality of groups of first line finders;

60 Fig. 3 shows a two-wire junction circuit outgoing to another automatic exchange and adapted to be associated with a printing register whereby a tangible printed record may be produced for each call established over the junction;

65 Fig. 4 shows a control circuit common to a plurality of outgoing junction circuits and adapted to be connected to the outgoing junction for a portion at least of the duration of its occupation by a call;

70 Fig. 5 shows an identification starting circuit and distributor;

75 Figs. 6 and 7 which should be placed one above the other show alternative identification equipment.

80 The ticket printing machine to which the bracketed conductors of Fig. 3 extend may be of the type disclosed in British Patent 472,435 granted to L. Devaux.

85 Referring to Fig. 1, when a subscriber at substation S originates a call to a subscriber in another exchange reached over the outgoing junction shown in Fig. 3, a first line finder such as 1LF is caused to rotate until its brushes a^1 , b^1 , c^1 , d^1 rest upon the terminals of the calling line, a second line finder such as finder 2LF is caused to rotate until its brushes a^2 , b^2 , c^2 , d^2 rest upon the terminals individual to the aforesaid first line finder and a register circuit (not shown) is caused to associate itself with the aforesaid second line finder in a well-known manner. The calling subscriber then dials the number of the wanted subscriber and the register causes the first group selector 1GS permanently associated 90

- with the second line finder 2LF, to select an outgoing junction, Fig. 3, in response to one or more digits of the number dialed, e. g., the first two digits of a five digit number. The register is 5 adapted to await the closure of a low resistance loop across brushes a^2 , b^3 , of the first group selector 1GS before transmitting each of the remaining digits, e. g., the last three digits of the number dialed.
- 10 When the outgoing junction circuit, Fig. 3, is seized, relay C_w energizes to earth on the c wire and energizes J_g . Contacts $fg5$ remove earth from wire 6 extending to the ticketing machine. Relay J_c now operates via $je2$, $ri2$, $si1$, $fg2$, followed by R_t ; R_t , $jd1$, $jc3$, $nf6$, $fg1$, to earth on wire 5 from the ticketing machine associated with the junction circuit. Relay J_d energizes via $es6$, resistance R_{ST} , $jsm2$, $es4$, $ri2$, $si1$, $fg2$, and operates JSM via $ac4$, $ps2$, $jd3$, $fg2$.
- 15 20 Relay J_b energizes via $fg5$, $je6$, a loop circuit via the junction and the incoming junction circuit, $je1$ and coil JA . B_b also operates via $ri6$, $es1$, $jb1$, $fg2$.
- 25 J_s is now looped across the incoming a and b wires and operates followed by J_l , and J_e ; J_e , $bb3$, $je4$, $js2$. J_e locks via $bb3$, $je5$, $fg2$. J_c also locks via $je1$, $jc2$, $js2$.
- 30 On the first impulse of the hundreds digit, J_s releases so that earth via $js2$, $je3$, $bb2$, Si , wire 1 extending to the ticketing machine operates Si and the printer magnet of the machine. Relay J_d is released followed by JSM so that switch J_S takes one step.
- 35 The locking circuit for J_c is also opened by $js2$ and J_c releases opening the loop circuit for J_b which releases.
- 40 An impulse is sent over the outgoing junction by the opening of the circuit of J_b , but on the release of J_s at the end of the incoming impulse, battery is connected via $fg4$, $jc5$, $si1$, to the junction b wire, and earth via $jc1$ to the junction a wire, to end the outgoing impulse.
- 45 J_s repeats the remaining impulses of the first digit to the printer magnet and over the junction. Relay Si remains energized until the end of the digit, when B_b is released at $si1$ disconnecting J_s from the junction to release J_s and to signal the register-controller. J_l is also released, together with J_e . Contacts $bb4$ maintain battery on the b wire when contacts $js1$ open to prevent an extra impulse being sent.
- 50 J_d reoperates in the same circuit as before followed by JSM . Earth connected to wire 2 by the ticketing machine is now connected via $jd2$, $ri3$, to wire 3 to cause the digit to be printed and the digit wheel to be returned to normal.
- 55 R_t has been locked via $ri1$, $fg1$ to wire 5 of the machine from which earth potential is now removed during the revolution of the operating 60 shaft MCS of the machine (not shown) so that R_t releases, followed by J_d and JSM , and J_S steps to its third position.
- 60 J_c now reoperates via $je2$, $ri2$, $si1$, $fg2$, followed by J_b .
- 65 70 When earth is reconnected to wire 5, when the machine is ready for the next digit, R_t reoperates via $jd1$, $jc3$, $nf6$, $fg1$, wire 5, and locks via $ri1$, $fg1$ to wire 5. J_d and JSM again operate, and B_b energizes via $ri6$, $es1$, $jb1$, $fg2$.
- 75 J_s is now connected to the incoming a and b wires to signal the register to send the tens digit. As before, J_l and J_e are operated and J_c locked.
- 75 The tens digit is transmitted and repeated by J_s to the machine and over the junction and switch JSM is stepped to position 4, after which

the same switching operations take place as after the hundreds digit, JSM being stepped to position 5. When the machine has printed the digit and signaled to the junction circuit, the latter in turn connects J_s to the junction to signal the register. The units digit is transmitted and repeated in the manner before described.

Switch J_S steps to position 6 during receipt of the units digit.

At the end of the digit, Si releases as before followed by B_b , J_e , J_s , and the circuit for J_l is opened.

J_d re-energizes together with JSM , and at the same time N_f is operated; N_f , $ri4$, $es6$, $Tm2$, $jsm2$ in position 6, $es4$, $ri2$, $si1$, $fg2$. N_f operates because resistance R_{ST} is no longer in its circuit as it was in positions 1—5 of J_S .

Contacts $nf1$ connect earth continuously to wire 3 to the machine to inform it that no more wanted party digits are to be awaited. The machine prints the units digit, and removes earth from wire 5 to release R_t which releases J_d , and J_S steps to position 7. N_f locks via $nf5$ and wire 4. Es operates via $ac3$, $nf4$, $fg2$.

Battery on the wire d from the preceding circuit operates Ew , via $ps5$, $es5$, $jl1$. Jl is slow-to-deenergize and will not release its armature before Ew energizes. The incoming a and b wires are now connected via winding of J_s to earth on $ew4$ and via $ew1$ and winding of J_s to battery. J_s reoperates and prevents Jl from releasing.

When the ticketing machine arrives in position 8, after printing the units digit, it removes earth from wire 4 to release N_f , which removes earth from wire 3. The machine then self-steps to position 10 and again connects earth to wires 4 and 5.

J_c is again energized via $je2$, $ri2$, $si1$, $fg2$.

Earth via wire 5, $fg1$, $nf6$, $jc3$, $jd1$ operates R_t , which locks via $ri1$, $fg1$ to wire 5. Es has been locked energized via $es2$, $fg2$ and now Ac energizes; battery, left-hand winding, $ps4$, $ri5$, $nf3$, right-hand winding, $es2$, $fg2$. Ac locks; left-hand winding, $ac1$, right-hand winding, $es2$, $fg2$.

When the called party replies, J_b energizes over the distant loop and earth via $fg2$, $jb1$, $es1$, $nf2$, $ar4$, energizes As .

Clock contacts CLC close and open every two seconds. At the first closure after As operates, earth via $as2$, CLC , $ss1$, $ts1$ energizes Fs .

When CLC open, Fs remains operated in series with the left-hand winding of Ss , $js1$ to $as2$. Ss also operates. When contacts CLC close for the second time, earth via the right-hand winding of Ss and the left-hand winding of Ts energizes Ts and holds Ss , the left-hand winding of which is short-circuited via $ts2$.

When contacts CLC open for the second time, earth via $js1$, $ts2$, Fs , $ts3$, right-hand winding of Ts holds Fs and Ts , but Ss releases since its left-hand winding is short-circuited and its right-hand winding has no circuit. On the third closure of contacts CLC , Fs is short-circuited and releases, but Ts holds via $ts3$, $ts4$, $ss1$, CLC , $as2$. JSM operates via $js2$, $ts1$, $fg2$.

On the third opening of contacts CLC , Ts releases, opening the circuit of JSM which steps switch J_S to position 8 in which Wp operates via $jl2$, $tm4$, $jsm2$, $es4$, $fg2$.

JSM is stepped in this manner after each six seconds of conversation starting from position 7.

If after one minute of conversation, the calling party's number has not been received by the ticketing machine, a facility governed by a manual key such as CRK may be brought into use to 75

cause the ticketing machine to skip the calling party's number positions.

If CRK is thrown, earth via *jsm2* in position 17, CRK, operates *Ns*, which connects *Nf* to wire 4. 5 *Nf* energizes to earth on wire 4, locks and connects earth to wire 3 to indicate end of calling party's number. The ticketing machine steps forward to position 22.

When *Ac* operated after the called party's 10 number had been registered, start and test battery via *ac5* operates relay *Cs*, Fig. 4, which in turn energizes *Is*.

Magnets *CJM* of all free ticketing control circuits are operated and the switches *CJ* hunt for 15 the outgoing junction circuit, Fig. 3.

When a switch *CS* finds, relay *Te* energizes; earth, *cdm1*, *Te*, *vp2*, *cjm6*, to start and test battery, Fig. 3. Double test is made by earth via *te1*, low resistance windings of *Dt*, *Te*, *vp2*, *cjm6*.

20 Contacts *dt2* connect earth to the filament circuit of valve *RV* via *vp1*. If the filament is in order it heats up. If the filament is broken, *Vp* energizes and releases *Te* and *Dt*. The circuit of *CJM* is opened at *vp4*, *Vp* locks at *vp1*, lamp *LO* is flashed and an audible alarm may also be given.

Vp may also be operated over its other winding if the battery supply fails or if the circuit is held for an unduly long time, in which case battery via *cam CM* first operates *Th* and later *Vp*.

30 If *Vp* does not operate, *Cs* is short-circuited and *Is* is released, *Vt* is energized via *tc6*, *dt1*, and contacts *vt4* connect 500 cycle current to grid transformer *AGT*. The valve *RV* becomes conducting and *Ap* operates followed by *Tc*, which 35 lights lamp *LO* steadily via *vp3*, *tc4*. *Vt* is released and 500 cycle current removed from *AGT* so that *Ap* releases. When the ticketing machine is ready for tariff it energizes *Ri* over wire 5, followed by slow-release relay *Pw* via *tc2*, *cjm1*, *ri2*, Fig. 3, *si1*, *js2*. Relay *Ic* also operates via *ed1*, *pw3*, *tf1*, *dt1*, followed by *Bd*; earth, *ccm2*, *Bd*, *ed4*, *ic2*, battery. The circuit for *Bd* is only effective when interrupter *INR* removes earth from *bd4*. When *INR* removes earth, *Bd* 45 energizes and connects *INR* to *Ir* which is operated when *INR* connects earth thereto. Earth via *ir2*, *bd1* energizes *CCM* until *INR* releases *Ir* when switch *CC* takes a first step.

During its operation *Ir* also connects earth 50 from *tf4* via *ir3*, *cjm3*, wire 1, Fig. 3, to the ticketing machine.

INR continues to impulse *Ir* which steps *CC* and the printer magnet of the machine in synchronization for the first tariff digit.

55 When the digit has been sent *Ed* is energized via *pw1*, *bd3*, *ccm1*, *cdm3*, *nt1*, *pit*. The operating circuit for *Bd* was opened by *ccm2* when *CC* stepped off normal, but earth via *db2* held *Bd* over back contacts *ed4* until *Ed* has operated. Release of *Bd* disconnects *INR* from *Ir* so that no more impulses are sent. Relay *Ic* is also released. Switch *CC* is homed; *CCM*, *bd1*, interrupter contacts, *ccm2*. *CDM* is operated via *ed3*. Earth via *ed2*, resistance *THR*, *tc3*, *cjm2*, *ps1*, operates *Jd*, Fig. 3, to signal to the ticketing machine that printing can take place. The machine releases relay *Ri*, Fig. 3. *Pw*, Fig. 4, is then released followed by *Ed*, which releases *Jd*, Fig. 3, and *CDM* so that switch *CD* takes a first step.

70 When the machine is ready for the next digit, *Ri*, Fig. 3, is reoperated, and *Pw*, Fig. 4, again energizes. *Ic* and *Bd* reenergize and a second tariff digit is sent by *Ir* under control of *Ed*, which operates when its circuit is closed via

cdm3 in position 2, and the cross-connection between the banks of *cdm3* and *ccm1*.

Four digits are sent out in this manner, switch *CD* being stepped to position 5 after the fourth digit is sent.

When the machine is again ready after the fourth tariff digit is printed, *Ri*, Fig. 3, and *Pw*, Fig. 4, energize and this time *Tf* immediately operates via *tf3*, *pw2*, *cdm3*, *nt1*, *pit*, and opens the circuit of *Ic*. Relay *Ir* energizes via *tf3*, *pw2*, *cdm3*, *nt1*, *pit*. Relay *Tf* locks in parallel with lamp *LA* via *tf2*, *tc1*, *cdm1*.

Earth via *ir4*, *th3*, *ir5*, is connected to start lead *SVL* for the distributor circuit Fig. 5 for the calling party identification control circuits. 15 At the same time, 2000 cycle identification current is connected via *ir4*, *tf5*, *cjm5*, to the conversational fourth wire *d*, Fig. 3, over which the current flows back to the first line finder circuit and the calling party's line circuit. 20

In the distributor circuit, Fig. 5, *Sv* is energized and connects earth to the filament of valve *DV1* in parallel with relay *Ad* which will operate and give an alarm if the filament is faulty.

25 2000 cycle current passes over the conversational fourth wire, wipers *d3*, *d2*, Fig. 1, lead *12*, Figs. 2 and 5, *ad1* to grid transformer *RGT*. Valve *DV1* becomes conducting and relay *Rp* is energized. Earth via *rp1*, *sv2* energizes *So*, which in turn operates *St*.

30 Relay *Ab* is normally operated so long as *DS* has access to an idle identification circuit. If a call comes in while *Ab* is released, *A1* is energized to operate an alarm and a congestion meter.

35 Distributor switch *DS* is normally standing on an idle identification control circuit, Fig. 2. Earth via *st5*, *dsm1* is connected to the filament of valve *DV*, Fig. 2, and winding of relay *Vp* in parallel, and 500 cycle current via *st1*, *dsm2* is connected to the identification circuit. 40

If the valve *DV* is faulty, *Vp* energizes, locks via *vp1*, operates an alarm via *vp2* and lead *ALL*, flashes lamp *LO* via *Vp3*, earths lead *FTL* to operate *As*, Fig. 5, via *dsm3*, and busies the identification circuit to group relay *Ab*, Fig. 5 by 45 opening *Vp5*. If *As* operates and *Ab* is energized, earth via *ab1*, *as1*, energizes *DSM*, which releases *As* and is itself released by *As*, to step *DS* to the next identification circuit. If this is busy, earth via *gf1* back and *scm3* or *sdm3* off normal, or 50 earth via *gt1* front is connected to *FTL* to step *DS*, Fig. 5 on another step.

If the filament of *DV*, Fig. 2, is in order, the 500 cycle alternating current via *dsm2*, *VFL*, *ft4*, Fig. 2, *ft2*, *gt1*, transformer *GT* renders the grid of *DV* less negative. Relay *A* operates in the anode-cathode circuit of *DV*. Earth via *at1*, *gt2*, *gf2*, energizes *Str*. Earth is now connected from *ft6* via *str3* and lead *RTL* to operate *D*, Fig. 5. *D* operates *DR* which disconnects the 2000 cycle 60 current from the transformer *RGT*. Relays *Rp*, *So*, *St*, therefore release and 500 cycle current is disconnected from lead *VFL*, Fig. 2. Relay *D* also operates magnet *DSM*.

Release of *A* due to the removal of 500 cycle 65 current connects earth via *at1*, *str1*, *gf3*, *gt3* to operate *Gt* which locks via *gt4*, *gf4*, *str2*.

Magnet *CFM* is now energized via *gt3*, *gf3*, *str1*, *at1*, and switch *CF* looks for the link circuit forming part of the conversational connection. 70 When the link is found, 2000 cycle current via lead *12*, Fig. 2, *fd*, Fig. 5, wiper *cjm8*, Fig. 2, *gt1*, *GT* renders the valve *DV* conducting and *A* again operates. *Gf* is now energized via *gt2*, *at1* and locks via *gf4*, *str2*. *Gt* is now released followed 75

by A. Ft energizes via *ft3, lt3, gf3, str1, a1* and locks via *ft3, str2*. Earth via *ft2, cjm1* energizes *Df*, Fig. 5, to disconnect the 2000 cycle current from the banks of the switches CF. Relay *Ft* also releases D, Fig. 5, which in turn releases DSM and distributor DS steps on to another identification circuit.

- Magnet IFM now energizes via *t1, lf5, ft6* and switch IF hunts for an idle identification line 10 finder RI, Fig. 1, which has access to the lines connected to the link circuit to which CF is connected, under control of relay T. When an idle RI is found, T energizes via *ft5*, wiper *cjm3, ifm0*, cross-connection, *ifm3*, lead *8*, battery, Fig. 15 1. T disconnects IFM so that switch IF stops. *Lt* operates via *t1, lf5, ft6* and connects busy earth via low resistance, left-hand winding of T and *lt4* to busy the selected finder RI.

RI now hunts for the calling party's line; RIM, 20 Fig. 1, lead *1, ifm3, lt3, gf3, str1, a1*.

When RI finds, the 2000 cycle current via wipers *d3, d2, d1*, Fig. 1 flows via one of wipers *rima—rime*, lead *9, 10* or *11, cjm6, ifm7, lt1, lt2, gt1, GT*. Valve DV becomes conducting and A 25 again operates. *Lf* energizes via *lt5, gt2, a1*, and locks via *lf6, str2*.

Direct earth via *lf3*, connected to *ifm3* and *ifm0*, short-circuits T which releases followed by *Lt*. 2000 cycle current is disconnected from GT 30 and A releases. Earth via *id1* is now connected via *Ic, df2, lf2*, to battery, so that *Ic* energizes when short-circuiting earth via interrupter INT is removed. *Ic* then locks via *ic3*, energizes *If*, and connects INT to relay I.

On its first energization, I operates SCM, and 35 500 cycle current is connected via *TR, i3, ifm1, cjm6*, lead *9, 10*, or *11*, one of wipers *rima—rime*, wipers *d1, d2, d3*, of the line finders and group selector back to the automatic ticketing equipment.

When the interrupter INT releases I, SCM releases and steps switch SC to its second contacts, and the 500 cycle signal is removed. While I was operated, earth via *sdm1, i1* operated *Si* 40 which locks via *si1, if1*.

Earth via *scm4, ic2, sdm1, scm1, Df, lf1* operates *Df* which releases *Ic* to stop impulse sending. Switch SC homes; SCM, interrupter, *ic1*, and *ic2, scm4*.

Earth via *scm4* short-circuits and releases *Df* so that magnet SDM which was energized via *d3* is released and steps SD to its second contacts.

By jumpering the home contacts of *sdm1* to the third contact of *scm1*, two 500 cycle cancel impulses would be sent instead of one before operating *Df*.

The 500 cycle current cancel pulse sent back over the conversational fourth wire passes via *cjm5*, Fig. 4, *tf5* to grid transformer AGT. Valve *RV* becomes conducting, *Ap* operates, and earth via *ap1, vt1, Pi, tf6, th4* energizes *Pi* which energizes CDM.

At the end of the impulse *Ap, Pi*, CDM release 65 and switch CD steps to position 6.

Relay *Th* now energizes via *cdm3, nt1, pi1*, and locks via *th3, tf4*. Relay *Ir* is released when brush *cdm3* leaves position 5 and lamp *LA* ceases to glow. The 2000 cycle signal over the conversational fourth wire is disconnected at *ir4*, and the start signal is disconnected at *th3* from lead *SVL* so that relay *SV*, Fig. 5, releases.

In the identification circuit *Ic*, which was released when the cancel pulse had been sent, cannot reoperate to transmit the calling party's num-

ber until relays *If, Id* have released in turn to connect earth via *id1* to *Ic*.

When *Ic* reoperates, it again connects INT to I, so that simultaneously, under control of INT, 500 cycle impulses are sent back to the tick- 6 eting equipment and earth pulses are connected to SCM to step SC.

The first and second digits in the example given are exchange code digits and are therefore known. The second terminal of *sdm1* is cross- 10 connected to the required wire 1—8.

When the required number of impulses have been sent, *Df* is again energized via *scm1, sdm1*, and impulsing is stopped. *Ic, If, Id*, release in turn to give an interdigital period, *Sc* is homed 15 and *Df* is released stepping *Sc* to position 3. When *Ic* reenergizes, a second exchange digit is transmitted under control of a cross-connection between contact 3 of *sdm1* and a contact of *scm1*. 20

The thousands digit is then sent, the number of impulses being determined by a circuit via *sdm1* and its fourth contact, *cjm2*, and a contact of *scm1*.

The value of the hundreds digit is determined 25 by the connection via contact five of *sdm1*, wiper *cjm1* and the *scm1* bank.

The tens and units digits are determined by the connection via the sixth and seventh contacts of *sdm1, ifm6*, and *ifm5*, leads 6 and 5, and wipers *rimd* and *rime*, Fig. 1, in turn in the following manner.

There are four wires provided between RI and wipers *ifm1—ifm4* which connected to the arcs *scm1, scm2*. These four wires are successively 35 tested by relay *Df*, first for a direct ground and then for a ground through a resistance. In this way, one wire may indicate two different digits and the four wires provided suffice, therefore, for eight digits. For odd figures 1, 3, 5, and 7 40 the four wires are connected directly to the corresponding arc terminals on *rimd, rime*, whereas for the even figures 2, 4, 6, and 8 they are connected over resistances of 1500 ohms. Relay *Df*, after one step of *SC*, is connected to wire 4 and 45 operates if a full ground (digit 1) is connected to wire 4. Relay *Df* is shunted in this position by a 200 ohms resistance via *scm2, ft1*, so that it is not able to operate if the ground on wire 4 is connected over a resistance. In case of a full 50 ground, however, the shunt mentioned has no effect. If *Df* does not operate *SC* advances on the next impulse to position 2, where *Df* remains connected over arc *scm2* to wire 4. The shunting 55 resistance of 200 ohms is, however, disconnected and, therefore, if the wire 1 is grounded over a resistance of 1500 ohms (digit 2) *Df* will operate and stop sending. If this is not the case, *SC* continues to advance and the wires 2, 3 and 4 are consecutively tested in the manner described above. After eight steps, ground via *scm4* is disconnected from the brush of RI and *Df* now 60 checks via terminal 9 of *scm1*, whether the arc terminal of RI is grounded or not. In the former case *Df* operates (digit 9), whereas if the 65 terminal in question is not grounded *SC* makes a tenth step and *Df* now operates in any case by a ground on the tenth terminal of *scm1* (digit 0).

After the sending of the last digit, earth via *sdm2* short-circuits relay *Str* which releases and 70 causes the release of all relays involved into the connection. *SC* homes; *SCM* and interrupter *ic1* and *ic2, scm4*, and *SD* homes; *SDM* and interrupter, *sdm4, st1, a1*. When *SC* and *SD* are home, the circuit is available for a new call. 75

The trains of 500 cycle impulses identifying the calling party's number, impulse relay *Ap*, Fig. 4. Earth impulses via *ap1*, *vt1*, *Pi*, *t/6*, *th4*, *cjm3*, wire 1, Fig. 3, to the ticketing machine step the digit printer for each digit in turn. Relay *Pi* remains operated throughout each impulse train and energizes CDM. At the end of the first digit *Pi* releases followed by CDM and switch CD steps to position 1, in which earth via *pil*, *nt1*, *cdm3*, resistance THR, *tc3*, *cjm2*, *ps1*, operates *Jd*, Fig. 3, to signal the machine to print the digit. The machine releases *Ri* which releases *Pw*, Fig. 4, until the machine is ready to receive the next digit when *Ri*, *Pw* reoperate. *Pi* operates during the second digit to release *Jd*, Fig. 3.

At the end of the second calling party's digit, CD steps to position 8, *Jd* reoperates and signaling between the control circuit and the machine takes place as before.

Three more digits are received and at the end of the fifth digit CD steps to position 11. Earth via *pil*, *nt1*, *cdm3*, *tc3*, *cjm2*, *ps1*, operates *Jd* in the junction circuit, Fig. 3.

The earth via *pil*, *nt1*, *cdm3*, this time passes direct to *tc3* and not via resistance THR. In consequence when *Jd*, Fig. 3, energizes, the same earth via *ri4* operates *Nf* which locks via *nf5* and wire 4 to earth on the machine. *Ps*, Fig. 3, operates via *ac3*, *nf4*, *jg2*, and locks via *ps3*, *jg2*. Contacts *ps1* release *Jd*.

Earth via *nf1*, wire 3 causes the machine to step to position 22 in which earth is removed from wire 4 to release *Nf*, removing the earth which had been connected via *nf1* to wire 3.

Earth via wire 5 from the machine via *jg1*, *nf6*, *jc3*, *jd1* energizes *Ri*. The right-hand operating winding of *Ac* is now short-circuited via *ps4* operated, *ri5* operated, *nf3* in normal position and *Ac* releases.

Removal of battery on *ac5* releases *Te* and *Dt*, Fig. 4. Relay *Tc*, Fig. 4, also releases followed by *Tf*, *Th*, *Pw*. CD homes; CDM and its interrupter, *tc1*, *cdm1*. The ticketing control circuit, Fig. 4, is now back to normal and ready for use in another call.

In the junction circuit, the release of *Ac* is followed by operation of *Ar*, via *ns2*, *ac6*, *wp1*, *jg2*. As is released at *ar4* and *Jd* is operated via *wp2*, *ar1*, to ground on terminal 3 of CLC, connecting earth from *es3*, via *jd2*, *ri3*, to wire 3 in response to which three minute-holes are punched by the machine in turn on the ticket, and the date, hour, and serial number are printed in turn, one with the punching of each minute hole.

Ri is released during these operations by removal of earth on wire 5, and *Wp*, which no longer has a locking circuit via *wp3* since *Ac* is released and *Jd* is operated, is released since its locking circuit via *wp4*, *ri2* is also opened. The junction circuit is no longer held busy by the ticketing machine, *Jd* also releases.

It will be remembered that JS started counting conversation time from position 1, taking one step per 6 seconds or ten steps a minute. Earth via *ar5* has maintained the counting circuit operative in place of *as2*, *Ar*, being locked via *ar2*, *jg2*.

When JS reaches position 1 on its second rotation, earth via *jg2*, *es4*, *jsm2*, *ar6* operates relay *Tm* which locks via *tm1*, *jg2*.

JS has 22 positions, and its thirty-first step after position 1 on the first rotation determines the beginning of the fourth minute of conversation, that is, when it reaches position (7+31-22) 16 on its second rotation. In this position, *Wp*

is reoperated via *jl2*, *tm4*, *jsm2*, *es4*, *jg2*, followed by *Jd* via *wp2*, *ar1*. *Ri* has been energized via wire 5 after the three minutes have been recorded, and earth is again connected via *es3*, *jd2*, *ri3*, to wire 3 to initiate recording of the fourth minute. *Ri* is released by the ticketing machine and when JS steps to position 11, *Wp* which has no locking circuit releases followed by *Jd*. When the fourth minute has been recorded and *Jd* has been released *Ri* is reoperated to earth on wire 5. 10

With *Tm* energized, JS steps to its first position immediately it reaches position 21; *JSM* and its interrupter, *tm3*, *jsm2*, *es4*, *jg2*. Thus after passing position 16 on the second rotation, JS only takes 20 steps per rotation at six second intervals, and the beginning of each additional minute occurs when JS reaches positions 6 and 16 during each further rotation, the recording being caused by operation of *Wp* as before. 15

When the calling party hangs up at the end 20 of conversation, *Js* is released followed by *JL*. Earth at *jl1* is removed from the locking circuit of *Ew*. This earth is the holding earth for preceding equipment in the exchange. If a record is being made on the ticketing machine, earth 25 via *wp5* will hold *Ew* and the connection until the record is completed.

When *Ew* is released, the preceding equipment also releases and removes earth from lead *c* so that *Cw* releases followed by the main hold relay *Jg* which releases all operated relays. Switch *JS* homes *JSM* and its interrupter, *jsm3*, *jg5*. The junction circuit is now ready for use in another connection. 30

If the tariff to be charged in slack periods, 35 e. g., at night, is different from that charged at other times, a relay *Nt* is provided and is operated from clock-controlled contacts via *vt6* to substitute wiper *cdm2* for wiper *cdm3* in the tariff-signaling circuits. 40

Referring now to Figs. 6 and 7, the identification start impulse over conductor *SVL* from the junction circuit used in a connection energizes relay *Gs*, Fig. 6, which in turn energizes *Gb* in series (via *ri4*) with relay *Ot* of an identification control circuit of the group controlled by a relay *Gb*. If all the circuits of this group were busy relay *Ng* would be operated to extend the start circuit to another group of identification control circuits. *Vd* now operates via *vc3* and *ot1* and 45 causes *Vc* and *Do* to energize. The circuit of *Vd* is opened at *vc3* and it releases slowly, 2000 cycle current is connected during the time *Vd* is energized via *vd2*, *do2*, primary of transformer *DT*, *do4* to earth. The current induced in the secondary of *DT* causes anode current to flow in valve *DV* if the valve is functioning and relay *Ar* energizes. Relay *Ok* then operates via *vb2*, *ar1*. *Vc* has locked via *vc3*, *ot1*, and *Ok* locks via *ok3*, winding of *Vb* to *vc1*. *Vb* operates. 50

It will be noted that the circuit via *Vd* was opened when *Vc* operated and a test of the valve therefore takes place during the slow-release time of *Vd*. If the valve is defective and therefore *Ar* and *Ok* do not energize, *Va* will energize via back 55 contact *vd3*, when *Vd* releases, front contact *vc2*, to back contact *ok4*. The opening of contacts *va2* would release relay *Ot* and thereby release the control circuit. Relay *Va* will lock up over its right-hand winding and flash lamp *BAL*. 60

Assuming that the valve is functioning correctly, when *Vd* releases *Ar* and *Do* release. 70

Magnet *IMM* now operates via *ot2*, *fh2*, *ok1*, *ar1* and switch *IM* hunts for the group lines comprising the calling subscriber. When the 200 75

- line group is found, high frequency signal current via the third wire of the subscriber line and the condenser connected thereto passes via the wiper of switch IM to which the group of twenty subscribers' lines including the calling subscriber's line are connected, rectifier W of a bridge rectifier, e. g., R₁, v₁, o₁, t₁, r₁, p₁, d₁, primary of DT, d₂, rectifier Y to earth. The 2000 cycle current induced in the secondary of DT valve 5 DV conducting and relay Ar operates. Earth via front contacts of a₁ and v₂ passes via back contacts of a₅ to operate relay Bt. A direct current test relay Mt is now connected to test for double connections; earth, a₁, m₁, m₂, m₃, r₁, 10 15 high resistance winding of Mt, b₁, t₁, i₁, m₁ to test battery. If no other identification control circuit has stopped on the same outlet Mt will operate and lock over its low resistance winding in series Md which also energizes. 15 20 Relay Dc was energized when Bt operated via b₂, f₄.

If due to a double test, Mt does not energize, magnet IMM reoperates via o₂, d₁, m₁ and the finder IM resumes its search. Assuming that 25 Mt and Md operate, the low resistance ground via Md, Mt on wiper i₁ busies the selected outlet of the IM switches.

When Md energizes, magnet IFM is operated via m₂, f₁, f₁ and IF hunts for an idle final 30 selector in the group marked by the position of IM. When a selector is found Ft energizes: earth, d₂, i₁, f₁, m₁, f₁, m₁, i₁, m₅ and wire 2 to idle battery potential on the final selector (FS) c wire. The double test is performed by 35 F_d and F_t and if IF is the only switch testing the final selector FS, F_d also operates followed by F_t to o₃ and Do to f₄. Contacts f₄ open the circuit of Dc which releases slowly.

Relay Ar which has been energized by the 2000 40 cycle current via IM is released by the operation of Do and Af energizes via d₁, a₂, f₂, o₁, a₁. Af locks via d₁, a₂ and energizes Ta via a₄, i₂.

A fundamental circuit is now completed: earth, a₁, o₁, f₂, a₃, Os, i₂, wire 1, b wire 45 of final selector FS and a relay F₁ therein (not shown). Relays Os, F₁ energize. Earth via o₁, u₁ energizes magnet MTM of the 11-point digit storage switch MT.

The operation of F₁ in FS causes the trip spindle to rotate and send back revertive impulses over the fundamental circuit, in response to each of which Os is released to step switch MT.

Earth via d₄, primary of DT, d₂, u₄, m₃ is connected in turn to wires 1—10 connecting 55 the bank of m₃ to wipers i₁—i₁₀. When the i₁₀ wiper to which 2000 cycle potential is connected is reached, relay Ar reoperates, opening the fundamental circuit to stop FS and MT. Relay It now energizes via a₅, v₂, a₁, followed by Us via i₂, a₄.

Contacts u₄ open the circuit of Ar which releases and again closes the fundamental circuit. Us locks via u₃, a₄, and It is released. The circuit of the primary winding of DT now passes via d₂, u₄ operated, 125 cycle filter, i₂, wiper i₁, wire 3 to the final selector test wiper.

The release of F₁ in FS advanced the sequence switch in known manner into the position for units selection and its reoperation on the reconnection of the fundamental circuit causes the brush carriage to rotate.

This time the revertive impulses are repeated by Os, via o₁, u₁ to magnet MUM of 22-point storage switch MU. When the brush carriage in 70 the final selector FS reaches the terminal to the

c wire of which 125 cycle potential is connected, Ar is operated, whereupon Os and F₁ in FS are released and the brush carriage stops. The marker MU has made the same number of steps as the brush carriage of the final selector FS. 5 Relay It is reoperated and contacts i₁ connect battery via i₁ and lead 4 to operate a special relay in FS to suppress private branch exchange hunting. If the calling tone persists for sufficient time It will release slow-release relay Ta. 10 This arrangement ensures that the brush carriage has stopped on a marked terminal, and has not been stopped by potential kicks produced by changes in the direct current conditions on a subscriber's c wire. 15

Earth via a₁, v₂, a₅, u₂, t₁, energizes relay Lt.

The identification circuit has been held by the earth potentials supplied by contacts of O_t during the above operations. 20

During sending, earth via a 125-cycle filter is connected via U₅, m₃, i₁ wiper to the multiple point connection of the twenty marking wires including that of the calling line. This prevents low-frequency interference between the 25 individual marking wires, while allowing an identification circuit to deal with another connection in the group.

If a premature release had taken place, O_t would have released the circuit, unless there is 30 another call at the same time.

If a premature release occurs while the final selector brush carriage is hunting, and the identification circuit is held by another call, FS will not find a marked outlet on the selected level and 35 switch MU will take 21 steps. Relay R₁ is therefore energized via m₂, i₁. R₁ locks via r₂ and releases O_t and the other relays. Relay X operates via interrupters of MTM, MUM, m₂, a₁, and closes a circuit via x₁, m₁, for MTM. 40 Relay X interacts with MTM and MT homes. Relay X then interacts with MUM and MU homes. Earth is then connected via a₁, m₂, m₁, r₁ to short-circuit and release R₁.

Assuming that the conversation continues, 45 relay Cw energizes via i₂, i₁, lead 3, and the c wire of FS, in parallel with the calling subscriber's cut-off relay, and earth via c₁, holds O_t. If release takes place during transmission of the calling party's number, Cw and O_t will 50 release, and the identification circuit will return to normal.

The various digits are determined in the following way and are transmitted in well-known manner. In a six-digit area, the first two digits 55 are known from the office. These two invariable digits are sent in positions 1 and 2 of a sequence switch respectively.

The 1000's digit is determined by the position of IF, or in other words, by the group to which 60 the engaged final selector belongs. The 100's figure is a function of the position of IF and that of the marker MU. As known, one group of final selectors gives access to 200 subscribers (odd-even hundreds). In the case of even hundreds, MU 65 has received maximum 10 impulses only, during the units selection, whereas in case of an odd hundreds the final has sent 10 impulses more.

The 10's digit is indicated by the position of 70 MT.

The units digit is sent under the control of MU.

What is claimed is:

1. In a telecommunication system, calling lines having marking terminals, two groups of identifying switches of which one group is used for 75

5 terminating connections on said lines, means for imposing a test condition on the terminal of one of said calling lines, and means responsive to the presence of said test condition on said calling line for operating a switch in each of said groups of switches to connect with said terminal.

10 2. In a telecommunication system, calling lines arranged in groups having both group and line marking terminals, a group of switches for line group identification, a group of switches for line identification, said last-mentioned group of switches being also used for extending talking connections to said lines when called, means responsive to a calling line initiating a call for imposing a test condition in the group terminal and the line terminal of said calling line, means for operating one of said line switches for locating the terminal of said calling line, and means for operating one of said group switches for locating 15 the group terminal of said calling line before said line switch locates said calling line terminal.

20 3. In a telecommunication system, calling lines arranged in groups, each of said lines having a marking terminal, a group identifying switch and a line identifying switch accessible to said terminals, and a common test device associated with said group identifying switch for controlling the operation of said group identifying switch and of said line identifying switch when operated to locate the marking terminal of a calling line, said line identifying switch also serving to complete talking connections to said lines when called.

25 4. In a telecommunication system, calling lines having marking terminals, a called line, a group switch, switching selectors for establishing a connection between one of said calling lines and said called line, means for imposing a test condition on the terminal of said calling line, and means 30 responsive to the presence of said test condition on said calling line for operating said group switch to locate the group in which said calling line belongs and one of said selectors to locate the marked terminal in said group belonging to said calling line.

35 5. In a telecommunication system, calling lines arranged in groups and having marking terminals, called lines, a group identifying switch, final selectors for completing connection between calling lines and called lines, means for imposing a test condition on the terminal of one of said calling lines, and means responsive to the presence of said test condition on the terminal of said calling line for operating said group switch to locate the group in which said calling line belongs and one of said final selectors to locate the marked terminal in said group which belongs to said calling line.

40 6. In a telecommunication system, calling lines arranged in groups having both group and line marking terminals, a first group switch having access to said group marking terminals, a group of connector switches having access to said line marking terminals, and a second group switch 45 for engaging a free connector switch in said group of connector switches to connect with the line marking terminal of a calling line.

7. In a telecommunication system, calling lines having group marking terminals and line marking terminals, a group switch, final connectors for establishing connections to said lines when called, means for imposing a test condition on 5 the group marking terminal of a calling line, means for imposing a different test condition on the line marking terminal of said calling line, means responsive to the presence of said test condition on the group marking terminal of said calling line for operating said group switch to locate said group marking terminal, means responsive to the engagement of said terminal by said group switch for seizing one of said final connectors to locate the line marking terminal of said 10 calling line, and means responsive to the test condition on said line marking terminal for stopping the operation of said final connector.

15 8. In a telecommunication system, calling lines having group marking terminals and line marking terminals, a group switch, final connectors for establishing connections to said lines when called, means for imposing a test condition on the group marking terminal of a calling line, means for imposing a different test condition on the 20 line marking terminal of said calling line, means responsive to the presence of said test condition on the group marking terminal of said calling line for operating said group switch to engage said group marking terminal, means responsive to the engagement of said terminal by said group switch for seizing one of said final connectors, and a counting circuit for selectively operating said final connector by revertive impulses including means responsive to said test condition on the group marking terminal for causing said connector to select the group marked by said test condition and other means responsive to said 25 different test condition on the line marking terminal for engaging the terminals of said line. 30

35 9. In a telecommunication system, calling lines arranged in groups having a marking terminal for each group and a marking terminal for each line, a group switch, groups of final connectors having access, respectively, to each of said groups 40 of lines, means for imposing a test condition on the group marking terminal of a calling line, means for imposing another test condition on the line marking terminal of said calling line, means responsive to said group marking terminal test condition for operating said group switch to engage said group marking terminal, means responsive to the engagement of said group marking terminal by said group switch for determining the group of final connectors having access to the line group containing the calling line, means for selecting a free connector in said group of connectors, and means responsive to said test condition and to said other test condition for selectively operating said connector to engage the 45 terminals of said calling line. 50
